US00D886258S

(12) **United States Design Patent** (10) **Patent No.:** **US D886,258 S**
(45) **Date of Patent:** **** Jun. 2, 2020**

(54) **HEATER**

(71) Applicant: **IRIS OHYAMA INC.**, Sendai-shi, Miyagi (JP)

(72) Inventor: **Masaharu Sakamoto**, Kakuda (JP)

(73) Assignee: **IRIS OHYAMA INC.**, Sendai-shi (JP)

(**) Term: **15 Years**

(21) Appl. No.: **29/669,075**

(22) Filed: **Nov. 5, 2018**

(30) **Foreign Application Priority Data**

May 10, 2018 (JP) 2018-010153

(57) **CLAIM**

The ornamental design for a heater, as shown and described.

DESCRIPTION

FIG. 1 is a front, top and right-side perspective view of a heater showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof; and,

FIG. 7 is a left-side view thereof.

The broken lines shown represent unclaimed subject matter of the heater and form no part of the claimed design.

1 Claim, 7 Drawing Sheets
